**METHOD OF MANUFACTURING
JEWELRY PARTS**

ABSTRACT OF THE DISCLOSURE

A method of manufacturing jewelry parts comprising the following successive steps: coating rigid base pieces with a layer of congealable varnish; and while the varnish is tacky, depositing the base pieces onto a layer of finely divided decorative particles supported upon a flat pliant sheet; then agitating the base pieces by manipulating the said sheet so as to cause adherence of the particles to the tacky surface of the varnish; and after removal of any excess of the particles, and upon the coated surface becoming sufficiently dry and before complete congealation of the varnish, pressing the adhering particles into the congealing varnish by further manipulation of the pliant sheet, thereby producing a smooth surface on the resultant jewelry parts.

My present invention relates broadly to the field of costume jewelry and more particularly relates to the process or step by step method for manufacturing plural colorful parts from which various types of decorative jewelry, baubles, and beads may be assembled.

The present invention provides a method for manufacturing finished jewelry parts from inexpensive base material, for example macaroni products, in relatively large quantities thus keeping the cost for producing the costume jewelry at a minimum, and is an improvement over my previously issued Canadian Patent Number 683,627, dated April 7, 1964, which discloses improved steps that I have developed, and which specifically render the time required to produce jewelry parts of better finished quality, when compared with those produced under the process of said Canadian patent, at a considerable savings of time.

The invention consists principally in improving the steps employed to apply scintillating particles or glitter to provide a pleasing surface appearance and, further, to imbed said particles into a varnish coat covering a rigid base or body to which the finish is applied and which dictates the general configuration of the finished jewelry part.

In order that my improved method may be clearly understood, I shall explain one manner in which it may be carried out in connection with a base material of a macaroni product which I have found to be desirable from the standpoint of availability at an economically feasible cost per price.

To be economically practical, it is desirable to submit a relatively large quantity of pieces of the base for the jewelry part to the several steps of this method simultaneously since, obviously, doing one piece at a time would require such an expenditure of time as to result in a final cost approximating jewelry utilizing precious metals and gems and thus destroy any possible market.

One shape and size is chosen from among the many macaroni products now available on the market which choice will dictate the final jewelry part shape and size desired by the operator. This may or may not be one of the products of tubular configuration; that is, one having a central aperture, depending upon how the jewelry part is to be finally mounted. Obviously the finished parts may be mounted by one of the well known methods for mounting decorative items, such as by stringing, by employing

2

an adhesive, by confinement under malleable metal fingers or otherwise as found desirable.

When one employs the macaroni products having a central aperture as for example that conventionally termed, "salad macaroni," it is necessary to insure that the central aperture is not filled or unduly diminished so as not to preclude it from being strung on a string. This may be easily accomplished by applying each coat of varnish as a very thin coat employing a viscosity reducing agent as found desirable to provide a fluid in which the viscosity of the varnish is such that the surface tension will rupture any film that may form at an orifice of the central aperture.

There are a number of ways in which these macaroni products may be provided with one or more layers of congealable varnish. For example the base parts may be spread over a surface and the varnish may be applied by hand with a brush or sprayed on from a pressurized can as revealed in my said Canadian patent, or alternatively by means of a device such as that disclosed in patent 2,622,042, dated December 16, 1952, wherein the pieces may be moved on conveyors, and coated or strung on strings and dipped. For an acceptable practice of this invention it is sufficient to provide a rigid supporting base with at least one layer of a congealable varnish.

By varnish I mean any natural or artificial product resembling varnish which through natural drying or applied heat or other agents will congeal into a hard coating material. Obviously the varnishes may be clear or of any desired color to result in a jewelry part having the aesthetic qualities desired. Also the base may be provided with any number of coats of varnish consonant with maintaining a central aperture, where this type of base is selected, and in combinations of colored and clear to further enhance the final appearance of the jewelry part.

It is required, however, in the practice of the present inventive method that prior to the herein defined steps the decorative jewelry parts be provided with a coat of congealable varnish wherein the surface is still in a tacky condition. In this tacky condition, the jewelry parts may stick together except for the fact that the cohesive strength of the varnish, wherein the viscosity is reduced as aforesaid, is not sufficient to support the weight of a jewelry part; that is to say, if two of the jewelry parts are stuck together and one is elevated, the other will fall away therefrom since the gravitational pull exerts a force greater than the cohesive force of the varnish.

Jewelry parts having the tacky varnish surface are deposited upon a thin layer of finely divided, decorative, free particles commonly known as glitter which reflect light and thus appear to scintillate. These particles may vary in size but it has been found that a practical range of sizes is in those particles which are larger than dust, passing through a sieve of say 40 mesh, and smaller than those largest particles that will pass through a sieve of say 20 mesh. Obviously, however, the size of the particles will be proportional in some degree to the size of the supporting base and whether or not it has an aperture through which a string is to be passed.

Said layer of finely divided decorative particles shall be sprinkled upon and supported by a pliant sheet laid upon a substantially flat surface. The term "flat" is here used to mean any surface sufficiently horizontal and free of undulations which would, because of its own divergence from horizontal, cause the base parts to roll or tumble by gravitational force. The deviation obviously may be greater with rectangular shapes than with more or less spherical configurations. The sheet may be formed of any material suitable for supporting the decorative particles and sufficiently pliable to admit of manipulation

as hereinafter more particularly described. I have used pliant sheets of plastic material ranging in thickness from .25 mil to 2 mils and have found while all of these materials are usable, those of the very thinnest gauge are too delicate and require extreme care to prevent rupture of the sheet, thus slowing the process of manufacture in accordance with this disclosure. Those in the heavier gauges are less pliable and to this degree require a longer time of manipulation to produce the desired results. I therefore recommend though I do not limit the invention to using a pliant sheet of plastic material, having a thickness of approximately 1 mil; however, the material need not be plastic, but may be a finely woven cloth, where the size of the particles is such that they may not pass through the cloth and the texture of the cloth is such as to preclude adherence of the particles to the cloth to any great degree.

Preferably, though not absolutely necessarily, after the supporting base having an outer layer of tacky congealable varnish is disposed upon the layer of finely divided decorative particles I sprinkle from a container having a perforated top over the top of the plural bases an additional quantity of the decorative particles to facilitate rapid covering of the supporting bases. This precludes, as much as possible, the sticking together of two or more supporting bases during initial manipulative movements of the sheet wherein the pliable sheet may be manipulated by raising the peripheral edges to form a bag-like container and manipulating the contents as by shaking, jarring, kneading, or otherwise agitating the bases in the presence of the decorative particles until all of the outer tacky surfaces of the bases are covered to the degree desired.

The quantity of the parts so treated are spread again into a thin layer and permitted to dry sufficiently so that the surface of the varnish becomes dry and yet complete congealation of the subsurface varnish has not taken place, before, during or after which the excess decorative particles are sifted therefrom. The time required for this drying will vary depending upon the volatility of the varnish used, and the humidity and temperature of the atmosphere wherein the parts are disposed. Artificial drying means such as a heated drying oven or heat lamps materially speed this drying process and also should the operator desire, periodic repositioning of the parts by stirring or agitation will further decrease the time required to dry the surface of the varnish.

At this time, with the varnish dry on the surface only, the quantity of jewelry parts and again manipulated in the pliant sheet. This may be the same pliant sheet or another similar sheet as found desirable, at which time the tumbling of the parts upon each other causes the pressures generated among the parts and between the parts and the pliant sheet to press the decorative particles into the congealating subsurface varnish and thus produce a smooth surface. To assist in this step it is helpful to knead the jewelry parts through the pliant sheet by use of the hands or mechanical means, that is, by applying pressures through the outer surfaces of the now bag-like pliant sheet to the jewelry parts and speeding the process of smoothing these surfaces. The parts are then spread into a layer again and permitted to complete the congealation process, after which they may be strung upon a string. A final coat or number of coats of clear varnish may be applied to give an appearance of depth to the jewelry part if desired.

While it is not frequent that two or more of the jewelry parts stick together by reason of the congealating varnish, those that may do so are separated during the second manipulation of those parts in the plastic sheet. Where this separation has taken place, there will be a minute exposed tacky surface at the point of separation on each of the parts, but it has been found that these surfaces pick up some of the decorative particles which may have been added or loosened during manipulation,

and are thus not visible to the eye at the end of the second manipulation step.

By using the method herein described I can finish jewelry parts in quantity lots and secure a decidedly improved and desirable finished product having a smooth surface which will not catch upon the threads of sweaters and other wearing apparel. Also these improved steps enable one to produce desirable, smooth finishes in a very wide variety.

10 While I have described a preferred embodiment of my invention, I do not wish to be limited to the exact materials described herein because the scope of my invention is best defined in the following claims.

I claim:

15 1. The method of manufacturing decorative jewelry parts from rigid supporting base pieces having at least one layer of congealable varnish, wherein the improvement comprises the successive steps of: when the surface of said varnish is tacky, depositing said base pieces onto 20 a layer of finely divided decorative free particles supported upon a substantially flat pliant sheet; manipulating said sheet so as to effect agitation of said pieces sufficiently to cause adherence of said particles to the tacky surface of said varnish; removing any excess of 25 said particles not adhering to said jewelry parts; upon the said surface becoming sufficiently dry and before complete congealation of said varnish, further manipulating the pliant sheet containing said jewelry parts so as to press said adhering particles into said varnish, whereby 30 to produce a smooth surface on said parts; and thence effecting complete congealation of said varnish.

2. The invention defined in claim 1 and further characterized by including during one or more steps of manipulating said pliant sheet, manipulation by kneading 35 said parts contained within the said sheet through the sheet from the outside thereof.

3. The invention according to claim 1 wherein the varnish and the particles are selected from among groups including various colors.

40 4. The invention according to claim 1 wherein the base is a macaroni product of a preselected shape.

5. The invention according to claim 2 wherein the varnish and the particles are selected from among groups including various colors.

45 6. The invention according to claim 5 wherein the said base is a macaroni product of a preselected shape.

7. The invention defined in claim 1 and further characterized by applying a finish coat of varnish over the parts after the said final congealation.

50 8. The invention defined in claim 1 and further characterized by interposing the step of sprinkling an additional quantity of free particles over said parts while being deposited on said layer of particles before said first named manipulation of said sheet.
